HAND-OPERATED MECHANISM FOR PROPEL
LING BOATS AND CANOES

Aage I. Baastrup, Rutherford, N.J.

Application December 1, 1955, Serial No. 550,290

5 Claims. (Cl. 115—28)

This invention relates to a hand-operated mechanism for propelling row boats and canoes.

It is the principal object of the present invention to provide in a hand-operated mechanism for propelling boats and canoes reversing means wherein the change of direction of movement of the boat or canoe or the turning of the boat can be effected easily without stopping the motion of the mechanism.

It is another object of the invention to provide a hand-operated mechanism for propelling boats and canoes that will have propelling blades that swing open on the propelling stroke and close automatically on the return stroke, which are mounted upon vertically-swingable members that can be adjusted in a simple manner with the blades by hand-operated cables to change the propelling direction of the blades or to render the blades free from use and adjusted to a neutral position.

Other objects of the invention are to provide a hand-operated mechanism for propelling boats and canoes, which is of simple construction, inexpensive to manufacture, has a minimum number of parts, light in weight, adjustable to different width boats, easily installed upon the boat or canoe, easy to manipulate, compact, durable and rugged, easy to adjust, effective in use and efficient in operation.

For other objects and for a better understanding of the invention, reference may be had to the following detailed description taken in connection with the accompanying drawing, in which

Figure 1 is a perspective view of a boat and of the hand-operated mechanism of the present invention mounted thereon.

Fig. 2 is an enlarged transverse sectional view taken through the boat and looking in elevation upon the mechanism and upon both sides of the mechanism, this view being taken on line 2—2 of Fig. 1.

Fig. 3 is a side elevational view of the mechanism with the blades extended to the side of the mechanism to effect the forward propulsion of the boat.

Fig. 4 is a fragmentary elevational view of the mechanism with the blades extended downwardly and rendered ineffective, portions of the support arm being broken away to show an adjustable cable arrangement therewithin.

Fig. 5 is a side elevational view of the mechanism with the blades extended to the operative or forward face of the mechanism to reverse the direction of movement of the boat or canoe.

Fig. 6 is an enlarged fragmentary elevational view of the lower end of one of the arms as viewed on line 6—6 of Fig. 5.

Fig. 7 is an enlarged fragmentary sectional view taken through the cross arm and upon the handle for effecting the adjustment of the blades, this view being taken generally on line 7—7 of Fig. 4.

Fig. 8 is a sectional view taken through the shaft on which the cable-adjusting arm or lever is mounted and as viewed on line 8—8 of Fig. 7.

2

Fig. 9 is an enlarged longitudinal sectional view of the hand grip sleeve as viewed on line 9—9 of Fig. 2, and

Fig. 10 is a transverse sectional view taken upon line 10—10 of Fig. 3.

Referring now to the figures, 10 represents a boat having gunwales 11 and 12 to which the hand-operated propelling mechanism of the present invention, and indicated generally at 13, is connected for fore and aft movement by journal bearing brackets 14 and 15. The user of the boat will sit on a seat 16 and facing the rear of the boat in position to grasp the mechanism 13 along the top thereof. As the user of the boat pulls forwardly a rear thrust is made in the water in a manner to be later described to cause the boat to move forwardly.

This hand-operated mechanism 13 includes generally a top hand-grip bar or sleeve 17, adjusting sleeves 18 and 19, and depending arms 20 and 21 having respectively separable blade devices 22 and 23 thereon. Rods 24 and 24' extend through an upper bar assembly and into hand-grip sleeve 17. The rod 24 is fixed to the hand-grip sleeve 17 by a pin 17' while the rod 24' is releasably fixed to the sleeve 17 by a set screw 17". By this means, the rod 24' can be released from the sleeve 17 and the mechanism extended to adapt it for different width boats. Thereafter, the set screw 17" can be tightened to provide a rigid connection with sleeve 17 and between the rods 24 and 24'.

The adjusting sleeve 18 is secured by pins 26 and 26' to an inner sleeve 27 that is journaled in an opening 28 in the upper end of arm 20. On the inner sleeve 27 there is secured an operating lever 29, Fig. 8, that is held upon the sleeve 27 and against the spacing sleeve 30, by a washer 31 and a nut 32 threaded upon the end of rod 24. By turning the sleeve 18, the lever 29 can be adjusted or turned.

The adjusting sleeve 19 on the opposite end of the bar assembly and upon the rod 24' is similarly connected through a sleeve 28' to a lever 33 and secured against axial displacement therefrom by a nut 34 threaded upon the end of the rod 24'. The sleeve 28' similarly extends through the upper end of the arm 21. The arms 20 and 21 respectively have horizontal portions 35 and 36 that respectively extend through the bearing brackets 14 and 15. It will be apparent that the adjustable sleeves 18 and 19 can be turned relative to the handle bar 17 to adjust or turn the levers 29 and 33. The lower end of the arm 20 has bifurcated portions 37 and 38, Fig. 6, in which is journaled a transverse pin 39. Fixed to the pin 39 and lying between a bifurcated portion 37 and 38 for rotational adjustment therein is a vertically-extending swingable plate member 40 on the opposite sides of which are respectively fixed pulley elements 41 and 42 to which are respectively connected cables 43 and 44 by respective pins 45 and 46 and which run upwardly through the arm 20 and out of the horizontal portion 35 for connection with holes in the respective opposite ends of the lever 29 as indicated respectively at 47 and 48. Through the adjusting sleeve 18, lever 29, cables 43 and 44, pulleys 41 and 42, and the swingable member 40, which carries hingeably collapsible paddle blades 50 and 51 that are opened and closed as the mechanism is worked by a pull on the bar section 17, the swingable member with the blades can be swung to a neutral position from a position that moves the boat forwardly or continued through to a position that moves the boat rearwardly. When the lever 29 is turned to the horizontal position as shown in Fig. 4, the swingable member 40 is extended so that the blades 50 and 51 are lowered to a neutral position where they are ineffect-

tive upon the water. The blades are hinged to the lower edge of the swingable member 40 by double hinge sets 52 and 53. The paddle blades 50 and 51 are permitted to close in upon one another up to central stops 54 on the vertical edge of the swingable member 40 and adapted to extend between the blades 50 and 51, so that the blades can only close to within a slight angle from one another. By this means, the blades are readily separated as they are moved into the water.

The swingable member 40 is adjusted to have the blades 50 and 51 in the trailing position as shown in Figs. 1 and 3. At this time a shoulder 55 abuts the side of the propelling arm 20 and the swingable member 40 will be held in this position by an over center tension spring 56 connected to a mid-projection 57 on the swingable member 40 and anchored at an elevated point 58 on the propelling arm 20. The lever 29 will then have been adjusted into the position shown through an arc of forty-five degrees from a neutral horizontal position. As the adjusting lever 29 is turned from the neutral position in the opposite direction through forty-five degrees therefrom, the device 22 is reversed so that an opposite shoulder 55' on the swingable member 40 will engage the propelling arm 20 as shown in Fig. 5. When the levers 29 and 33 are adjusted to extend to a horizontal position the blade device will be extended to the position shown in Fig. 4 and ineffective when moved through the water. The mid projection 57 extends beyond the opposite sides of the edge of the swingable member 40 and respectively serves as stops for the blades 50 and 51 to limit their opening movement, Fig. 10.

As the user of the boat pulls on the bar assembly 17, the blades 50 and 51 will open and a forward thrust will be given to the boat. As the operator pushes rearwardly, the paddles or blades will fold together and pass easily through the water and be positioned for the next pulling stroke. To adapt the mechanism for reversing the operation of the steering of the boat, the hand sleeves 18 and 19 are turned to cause the lever to assume the position shown in Fig. 5. For turning the boat only one of the blade devices need to be adjusted to the reversing direction and that one depending upon the direction in which the boat is to be turned.

While various changes may be made in the detailed construction, it shall be understood that such changes shall be within the spirit and scope of the depending claims.

What is claimed is:

1. A hand operated mechanism for propelling boats and canoes which comprises a transversely-extending handle bar assembly, propelling arms connected at their ends to the handle bar assembly and adapted to be respectively attached to the respective sides of the boat for fore and aft swinging movement, a pair of hingeably collapsible paddle blades connected to the lower ends of each propelling arm for angular adjustment about a horizontal axis between forward and reverse propulsion and neutral positions, and hand operable means upon the handle bar assembly and propelling arms connected respectively to each pair of paddle blades whereby said blades may be angularly swung or adjusted between the

forward, neutral and reversing positions upon the handle bar assembly and while the propelling arms are being swung, the lower end of the propelling arm being bifurcated and the swingable member being disposed therebetween, and said hand operable means including pulley members connected to the swingable member and a lever mounted for pivotal adjustment on the upper end of said arm and cable cords extending downwardly through the propelling arm and connected respectively to the respective pulleys respectively in opposite directions thereover.

2. A hand-operated mechanism for propelling boats or canoes as defined in claim 1, and said swingable member having stop shoulders thereon adapted respectively to engage one side or the other of said arm as the blade devices are adjusted to the forward or reverse positions, and an over-center tension spring connected between the swingable member and the lower end of the arm and adapted to hold the swingable member by either of their shoulders against the lower ends of the propelling arms.

3. A hand-operated mechanism for propelling boats and the like as defined in claim 1, and said handle bar assembly comprising rod means extending through the upper ends of said propelling arms, adjustable handle sleeves revolvable upon said rod means and said levers being pivoted upon said rod means and fixed to said handle sleeves.

4. A hand-operated mechanism for propelling boats and the like as defined in claim 1, and said handle bar assembly comprising rod means extending through the upper ends of said propelling arms, adjustable handle sleeves revolvable upon said rod means and said levers being pivoted upon said rod means and fixed to said handle sleeves, and said rod means comprising two operating rods, an intermediate handle sleeve disposed between the adjusting sleeves, one of said rods fixed to said intermediate handle sleeve and the other rod releasably fixed to said intermediate handle sleeve whereby upon release of said rod the mechanism can be axially adapted for different width boats or canoes.

5. A hand operated mechanism for propelling boats and canoes which comprises a transversely-extending handle bar assembly, propelling arms connected at their ends to the handle bar assembly and adapted to be respectively attached to the respective sides of the boat for fore and aft swinging movement, a pair of hingeably collapsible paddle blades connected to the lower ends of each propelling arm for angular adjustment about a horizontal axis between forward and reverse propulsion and neutral positions, and hand operable means upon the handle bar assembly and propelling arms connected respectively to each pair of paddle blades whereby said blades may be angularly swung or adjusted between the forward, neutral and reversing positions upon the handle bar assembly and while the propelling arms are being swung.
